Primary Examiner — Michael C Stout*Assistant Examiner* — Eric Eldone Tormanen(74) *Attorney, Agent, or Firm* — Endurance Law Group PLC(57) **CLAIM**

The ornamental design for a base for surgical bur kit holder as shown and described.

DESCRIPTION

FIG. 1 is perspective view of a base for surgical bur kit holder according to the present invention;

FIG. 2 is a front elevation view of the base for surgical bur kit holder;

FIG. 3 is a right side elevation view of the base for surgical bur kit holder;

FIG. 4 is a left side elevation view of the base for surgical bur kit holder;

FIG. 5 is a rear elevation view of the base for surgical bur kit holder;

FIG. 6 is a top plan view of the base for surgical bur kit holder; and,

FIG. 7 is a bottom plan view of the base for surgical bur kit holder.

The dot-dash broken lines in depict the bounds of the base for surgical bur kit holder and form no part of the claimed design.
